UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,655, dated April 20, 1886.

Application filed November 13, 1885. Serial No. 182,756. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photographs, forming part hereof.

Figure 1 is a face view of my design. Fig. 2 is a cross-section of the raised portion thereon.

On each edge of the molding is a series of scallops, each scallop having one side, A, steeper than the other side, B. The surfaces 15 of said scallops are inclined or beveled toward the edge of the molding. Along the center of

the molding extends an elevation, C, above which is an elevation, E, and above the elevation E is a bead or elevation, D, having a rounded or convex upper surface. The lateral sides 20 of the elevation E are concave.

I claim—

The design for a molding, substantially as herein shown and described, which consists of the series of scallops on each edge of the molding, each scallop being steeper on one side than on the other, and the longitudinal elevations C D E. 25

FREDERICK MANKEY.
